HOT AND COLD WATER MIXING VALVE

Harry G. Bissell, Lebanon, Ohio, assignor to
Jordan Regulator Corporation, Lebanon, Ohio

Application July 23, 1948, Serial No. 147,726

Term of patent 14 years

(Cl. D78—1)

To all whom it may concern:

Be it known that I, Harry G. Bissell, a citizen of the United States, residing at Lebanon, in the county of Warren and State of Ohio, have invented a new, original, and ornamental Design for a Hot and Cold Water Mixing Valve, of which the following is a specification, reference being had to the accompanying drawings, forming part thereof.

Fig. 1 is a perspective view of a hot and cold water mixing valve, showing my new design.

Fig. 2 is a perspective view of the hot and cold water mixing valve of Fig. 1 turned one hundred eighty degrees.

I claim:

The ornamental design for a hot and cold water mixing valve, as shown.

HARRY G. BISSELL.
